No. 871,424.

PATENTED NOV. 19, 1907.

T. MAHONEY.
SURFACE ELECTRIC RAILWAY.
APPLICATION FILED JULY 6, 1906.

UNITED STATES PATENT OFFICE.

TIMOTHY MAHONEY, OF SAN FRANCISCO, CALIFORNIA.

SURFACE ELECTRIC RAILWAY.

No. 871,424.

Specification of Letters Patent.

Patented Nov. 19, 1907.

Application filed July 6, 1906. Serial No. 325,013.

To all whom it may concern:

Be it known that I, TIMOTHY MAHONEY, a citizen of United States, residing in the city and county of San Francisco and State of California, have invented new and useful Improvements in Surface Electric Railways, of which the following is a specification.

My invention relates to electric railways of the third-rail type.

10 Its object is to provide a system of distribution and a construction suitable for an alternating current with a third or single, sectional, surface conductor-rail, and which system will be perfectly safe, cheap to install, 15 cheap to maintain and which will avoid electrolysis of water and gas pipes, mains and the like.

The invention consists of the parts and the construction of parts as hereinafter more 20 fully described and claimed, having reference to the accompanying drawings, in which—

Figure 1 is a view diagrammatically illustrating the improved railway. Fig. 2 is a view in section of a switch. 25 A represents the ordinary track-rails traversed by the car 2, which is provided with the front and rear brushes or current collectors 3—4 traveling in contact with the sectional third or conductor rail 5. This rail 5 is arranged on the surface of the road bed and between the track rails and is divided into insulated sections which are preferably less than one-half of the length of the car. The brushes 3—4 are spaced from each other a 30 distance slightly in excess of the length of any one section of a track-rail so that both brushes may not be on one section of the rail at the same time. Arranged between the abutting ends of adjacent sections, are the 35 switch mechanisms by which the current is cut in to each section of the conductor rail; as the car passes over a section the current is cut in passing up through the car to propel the same, and thence being returned through the wheel axle and track rails to the original 40 source of power. These switches are of peculiar construction and form an essential feature of the present invention.

6 represents a solenoid, the coil of which is 45 suitably wound to prevent the passage of an alternating current through it; in other words, each coil is adapted as a choke-coil, as will be more fully explained hereinafter.

Each coil 6 is provided with a reciprocating core 7, one end of which is provided with an annular trough 8 adapted to contact, when the coil is excited to lift the core, with an annular contact-piece 9, which latter is connected through the wire 10 with the feed-wire 11. The upper end of the core 7 carries a cup 12 to contain mercury, and is adapted, when the core 7 is lifted, to engage a corresponding contact 13 and close the circuit between wire 10 and one section of the rail 5; the contact 13 being connected by a 60 suitable conductor 14 with one end of said section. The coil 6 has one terminal connected as shown at 15 with the same section of the rail and the other terminal of the coil is connected as at 16 with the adjacent end 65 of an immediately preceding section of rail 5. It will thus be seen that the several rail sections are connected in series through the coils and are connected intermittently in multiple through the conductors 14—7 & 10 70 with a feed-wire 11. The coils, however, are adapted to pass only a direct current and operate as choke-coils to the passage of an alternating current; it being the design of my invention to use an alternating current in the 75 work circuit for running the cars, and a direct current for the auxiliary circuit for operating the switch members 7. An ordinary alternating-current (A—C) equipment is used on the car.

17 represents an alternating current-generator or other suitable source of alternating current supply. From this source of supply the current is delivered to the main feed-wire 18.

At suitable intervals along the line of track, are transformers 19 by which the voltage in the main conductor 18 is suitably reduced, delivering to the sub-feeders 11 which supply the cars.

Any suitable means carried by the car are employed to excite the coils 6 successively. I prefer to use an alternating current to direct-current motor generator or rotary converter as 20 carried by the car; the motor 100 having one terminal connected as at 21 with the A—C conductor 22 on the car and the other terminal connected as at 23 with the return track rail through the car wheel. The positive terminal of the direct current end of 105 the generator 20 is connected through wire

24 with the brush 3, and the negative terminal is connected through the wire 25 with the forward brush 4 (assuming the direction of travel of the car to be as indicated by the arrow in Fig. 1).

The operation of the invention is as follows: With the car traveling in the direction of the arrow, or to the right, as in Fig. 1, the direct current generated by the generator 20 will pass through the wire 24 down through brush 3 to the section of rail 5 on which brush 3 is in contact, thence through the coil 6 immediately in advance of brush 3 through the rail section in advance and up through brush 4 and wire 25 to return. This direct current creates an excitation in the coil 6, which is included in the circuit, thereby lifting the switch-member 7, closing the work-circuit between the rail section with which brush 3 is in contact and the feed-wire 11. This work-circuit being of an alternating current will not flow through the coil 6 by reason of the counter-electro-motive-force which it induces, but will pass up through the brushes 3 into the car and thence to the controllers 26 and motors 27; afterwards returning through the car axles and track-rail. Each coil 6 is energized in turn as it is straddled by the brushes 3-4. As soon as the brush 3 passes beyond a coil, the direct-current circuit through this coil is broken, and also the alternating current circuit through the core or switch controlled by this coil is interrupted. With the coil becoming inert the switch-member 7 will drop down to original position on the spring 7^a carrying its contacts 8-12 away from their respective terminals 9-13, and without the formation of any arc at these points. Thus it will be seen that only one section of rail 5 will be alive at any one time, except for the short interval when the brushes span two insulated points in the sectional rail. The moment that the brush 3 passes off of section, the section is left "dead" and perfectly safe for pedestrians and others.

The various coils 6 and their switch mechanisms along the line must be suitably housed to exclude moisture. I prefer to use a casing made in two sections 28-29, with the upper section 29 seating in the enlarged flanged end 30 of the lower section 28 and upon a disk 31 of suitable insulating material which supports the coil 6. The casing and the protective disk 31 may be made of porcelain or terra cotta, or any other cheap and durable insulating material. I have made these casings of terra cotta in actual practice. The bottom and top of the casing are provided with suitable outlets for the respective wires 10-14-16.

Having thus described my invention, what I claim and desire to secure by Letters Patent, is

65 1. A third-rail system comprising a pair of

track-rails, a sectional conductor-rail, a car traversing the track-rails and provided with alternating-current-equipment, switch-magnet coils connected in series with adjacent sectional rails, said coils having a large reactance to oppose the passage of alternating currents, a source of alternating current supply, switch mechanism operated by said switch-magnet-coils to close a circuit between said source of alternating current-supply and the rail sections, and means carried by the car for supplying said magnet-coils with a direct-exciting current.

2. A third-rail system comprising in combination a pair of track rails at least one of which is electrically continuous, a car provided with alternating-current equipment traversing said track-rails, a sectional conductor rail, brushes on the car engaging sections of said conductor rail, solenoids connected in series with adjacent rail sections, said solenoids having a large reactance to oppose the passage of alternating currents, an alternating-current conductor, a source of alternating currents connected with said conductor and the track-rails, a series of transformers arranged along the line of track and having their primary coils connected between said conductor and said continuous rail, a series of feed-wires connected to the secondary circuits of said transformers, and switch members operated on excitation of said solenoids to close the circuit between one of said feed-wires and a respective rail-section, and a source of direct current supply carried by the car for exciting said solenoids.

3. In an electric railway system, the combination of a trackway having electrically continuous rails, a source of alternating currents connected to a supply conductor and with said rails, a sectional rail having the ends of adjacent sections connected through switch magnets whose reactances oppose the passage of alternating currents, feeders connected with said supply conductor, and means actuated by said switch magnets for connecting said feeders with said sectional rail sections.

4. In an electric railway system, the combination of a trackway having electrically continuous rails, a source of alternating currents connected to a supply conductor and with said rails, a sectional rail having the ends of adjacent sections connected through switch magnets whose reactances oppose the passage of alternating currents, feeders connected with said supply conductor, means actuated by said switch magnets for connecting said feeders with said sectional rail sections, and a car adapted to traverse said trackway provided with an alternating current equipment and having a direct current source to energize said switch-magnets.

5. In an electric railway system, a switch

mechanism comprising an insulating casing having telescoping sections, an insulating disk supported upon the lower section and held by the upper section, a solenoid coil supported upon said disk, fixed contacts secured respectively in the upper part of each section, and a solenoid core arranged to make contact with said fixed contacts.

In testimony whereof I have hereunto set my hand in presence of two subscribing witnesses.

TIMOTHY MAHONEY.
